UNITED STATES PATENT OFFICE.

JOHN BOUND, OF TUCSON, ARIZONA TERRITORY, ASSIGNOR OF ONE-HALF
TO JOHN C. WHITAKER, OF SAME PLACE.

CAR-COUPING.

SPECIFICATION forming part of Letters Patent No. 388,815, dated September 4, 1888.

Application filed May 17, 1888. Serial No. 274,215. (No model.)

To all whom it may concern:

Be it known that I, JOHN BOUND, a citizen of the United States of America, residing at Tucson, in the county of Pima and Territory 5 of Arizona, have invented certain new and useful Improvements in Automatic Couplers, of which the following is a specification, reference being had therein to the accompanying drawings.

10 In my drawings, in Figure 1, A represents a view of the front part of a railroad car; B, a lever by which the automatic clutch is released; D, the draw-head; F, the clutch, with a tongue or plunger, f, in position holding the 15 arrow-head H of the coupling-link P.

Fig. 2 represents a sectional view of the draw-head with the clutch F released and the arrow-head H of the coupling-link P in position of falling out.

20 Fig. 3 represents a sectional view of the draw-head with the clutch F and tongue or plunger f in the act of closing down upon the arrow-head H of the coupling-link P after the head of the link has been driven into the draw-head D.

25 Fig. 4 represents in section the draw-head on the line x x, Fig. 3.

Fig. 5 represents a form of lever for manipulating the device when attached to passenger cars.

30 Fig. 6 represents a double slotted link, being a modified form of link y.

In Fig. 4 the mortises m m are designed to receive the lock-bars a a, which pass through the front part of the clutch F in the slots c c, 35 which are so placed as to serve as guides to the lock-bars a a, giving them a divergent and outward direction into the mortises m m, thus securely locking and holding in place the clutch F. The tongue or plunger f is shown in position in the opening d in the clutch F to enter 40 the slot s in the coupling-link H on release of lever B, thus taking an additional hold upon the coupling-link.

The coupling-link P being out and pressure 45 on lever released, the forward part of the clutch F swings down on the bolt g by the action of gravity, assisted by the spring k, so that the shoulder forming its jaw N is perpendicular to the plane of the top of the draw-head D and approaching the jaw on D as nearly as the conformation will permit, the tongue or plunger

f projecting downward through the clutch F, the lock-bars a a carried down by the tongue f, with ends resting in mortises m m, the spring k released from tension and holding the parts 55 in place by pressure at the point q. In this position the draw-head is ready to receive the arrow-head H of link P, which, being forcibly inserted between the jaws N and L, comes first in contact with and drives up the tongue or 60 plunger f, which carries with it the lock-bars a a, releasing them from hold at m m. The clutch, being thus released, is carried up until the arrow-head H on the coupling-link P passes beyond the jaws N and L, the increased ten- 65 sion on the spring is released, the jaw of the clutch F falls over the shoulder on the upper side of the arrow-head H on the coupling-link P, the shoulder on the under side thereof falls behind the jaw L, the ends of lock-bars a a fall 70 into the mortises m m, and the tongue or plunger f drops into the slot s in the coupling-link P, thus grasping and holding the coupling-link in place with only sufficient play to accommodate the varying motions of the bodies coupled. 75

There is provided in the bottom of the draw-head D (shown in drawings, Fig. 3, at dotted line) a recess or excavation, r, forming a shoulder to receive the lower projection of the clutch F, for the purpose of relieving the main 80 bolt g, on which clutch F swings, from sudden concussion and strain of coupling. A projection at u upon the upper rear part of the clutch F falls against the solid cross top section of the draw-head D at the point v, which tends to relieve the strain on the main bolt g at the time of starting and in drawing. Relief is also provided to the main bolt g by the top of the clutch F coming in contact with a downward projection of the upper part of the draw-head 85 D at w when clutch F is locked in place. 90

The tongue or plunger f and lock-bars a a may be dispensed with, as the clutch F, when clasping the arrow-head H of the coupling-link P, will be held in place by gravity, assisted by 95 the spring k; but they should be used as an additional security, especially for heavy work. If dispensed with, the link y, by which the lever is connected, should be attached to the top of the clutch F.

I provide a hole through the upper front portion of the clutch F, behind the tongue or

plunger *f*, conforming to holes in the draw-head, to receive an ordinary coupling-pin in case of necessity. These holes are not in the drawings. The projection or teat *t* (shown in drawings, Fig. 2) on the lower and rear projection of the clutch *F* falls into the excavation *r* in the bottom of the draw-head *D* and assists in breaking the shock of coupling. It also comes in contact with the jaw *L* when the clutch *F* is thrown up and released, thus preventing the clutch from swinging up too far. I provide a continuous slot or series of openings in bottom of draw-head to admit of the escape of dirt and other matter that might otherwise accumulate and prevent the working of the parts.

Uncoupling is performed by raising the lock-bars *a a*, tongue or plunger *f*, and clutch *F* by means of the lever *B*, attached to the link *Y*, releasing the hold at *m m* and the grasp of the jaws *N* and *L* upon the arrow-head *H* of the coupling-link *P*, the formation of the lower arm of the clutch *F* being such as to act as an ejector upon the lower shoulder of the arrow-head *H* and throw it forward and out.

I prefer the link *Y* to be double-slotted, so that the purchase end of the lever and bolt passing through same at right angles can freely play up and down without obstruction.

Having thus described my invention, what I claim, and desire to secure by Letters Patent, is—

1. In an automatic coupler, the clutch *F*, having the jaw *N* and rear projection terminating at *t*, in combination with the draw-head *D*, having the jaw *L*, as and for the purposes described.

2. In an automatic coupler, the peculiar construction of the clutch *F*, having a rear projection with a concave inner surface, in combination with the coupling-link *P*, provided with the head *H*, operating in the manner described. 40

3. In an automatic coupler, the clutch *F*, having a rear and downward projection, as shown, in combination with the pin *g*, the spring *h*, and jaw *L* on draw-head *D*, as and for the purposes described. 45

4. In the herein-described automatic coupler, the clutch *F*, having the projection *u*, in combination with the pin *g* and solid cross top section *v* of the draw-head *D*. 50

5. In an automatic coupler, the lock-bars *a a*, in combination with the clutch *F* and mortises *m m* in the draw-head *D*, substantially as described. 55

6. In an automatic coupler, the clutch herein described, having the tongue or plunger actuated through a slot therein.

7. In an automatic coupler, the clutch herein described, having the tongue or plunger actuated by gravity, in combination with a slotted coupling-link. 60

8. In an automatic coupler, the clutch *F*, in combination with the tongue or plunger *f*, lock-bars *a a*, and the mortises *m m* in the draw-head *D*, as and for the purposes described. 65

In testimony whereof I have affixed my signature in presence of two witnesses.

JOHN BOUND.

Witnesses:

JAMES MACARTHUR,
ALBERT WELDON.
